United States Patent

Des. 235,310

Patented June 10, 1975

235,310

BOTTLE

Harold Anthony Betka, Waukegan, Ill., assignor to Abbott Laboratories, North Chicago, Ill.

Filed Aug. 2, 1973, Ser. No. 385,022

Term of patent 14 years

Int. Cl. D9—01

U.S. Cl. D9—10

FIG.1

FIG.2

FIG.3

FIG.5

FIG.6

FIG.4

FIG. 1 is a perspective view of a bottle showing my new design;

FIG. 2 is a top plan view;

FIG. 3 is a side elevational view;

FIG. 4 is a bottom plan view;

FIG. 5 is a perspective view of the bottle in an inverted position with the hanger withdrawn for suspension of the bottle for use; and

FIG. 6 is a fragmentary elevational view as viewed along the line 6—6 of FIG. 4.

I claim:

The ornamental design for a bottle, substantially as shown and described.
